Primary Examiner — Rhea Shields*(74) Attorney, Agent, or Firm* — Morris, Manning & Martin, LLP; Daniel E. Sineway, Esq.(57) **CLAIM**

The ornamental design for a medical equipment stand, as shown and described.

DESCRIPTION

FIG. 1 is a perspective view of a medical equipment stand, according to my new design;

FIG. 2 is a front view of the device of FIG. 1;

FIG. 3 is a back view of the device of FIG. 1;

FIG. 4 is a left side view of the device of FIG. 1;

FIG. 5 is a right side view of the device of FIG. 1;

FIG. 6 is a bottom view of the device of FIG. 1; and,

FIG. 7 is a top view of the device of FIG. 1.

In the FIG. 1, the broken lines are for the purpose of showing both environment and portions of the medical equipment stand that form no part of the claimed design. In FIGS. 2 through 7, the broken lines are for the purpose of showing portions of the medical equipment stand that form no part of the claimed design. In FIGS. 1 through 5 the stand is shown with a symbolic break in its length. The appearance of any portion of the article between the break lines forms no part of the claimed design.
